UNITED STATES PATENT OFFICE.

ALBERT KAUFMANN, OF BERLIN, GERMANY.

CASTING MACHINE.

Application filed June 9, 1924. Serial No. 718,926.

To all whom it may concern:

Be it known that I, ALBERT KAUFMANN, a citizen of Germany, residing at Berlin, Germany, have invented certain new and useful Improvements in Casting Machines, of which the following is a specification.

My invention relates to casting machines and more especially to machines of this kind which are operated by air or gas under pressure and comprise a movable casting reservoir which is charged with molten metal from a crucible through the tap hole.

In machines of this type as heretofore devised, the casting reservoir in order to charge it was dipped into a stationary crucible from above or the reservoir was stationary and the crucible adapted to be raised, or else both the reservoir and the crucible were stationary and the level of the fused metal in the crucible was raised above the discharge opening of the reservoir.

It is an object of my invention to provide a machine of the type described in which a movable casting reservoir cooperates with a stationary crucible, the movable casting reservoir having two operative positions. In one of these positions (charging position) the opening of the reservoir is connected with the tap hole of the crucible; in the other position (casting position) the opening of the reservoir is connected with the opening of the mould, the connection of the casting reservoir with the crucible being interrupted.

The tap hole of the crucible must be provided with a valve for closing it when it is not connected with the reservoir or it must be disposed at such a level and the machine must be so designed that it is possible to lower the level of the fused metal which as a rule is above the tap hole, to beneath said hole when the reservoir is not connected to the crucible.

In the first type of machine in which the crucible is provided with a valve for closing its tap hole, the valve is preferably so designed as to be open automatically when the mouth of the casting reservoir engages the crucible and is automatically closed again by the pressure of the fused metal. This arrangement involves the advantage that the gas pressure never acts on the valve in the crucible as no connection exists between the casting reservoir and the crucible during

casting. In consequence thereof this valve will always remain perfectly tight.

In the second type of machine in which the level of the fused metal in the crucible is lowered beneath the tap hole, this lowering can be effected by rocking the crucible about an axis disposed sideways of the tap hole. Or else a body may be provided in the crucible which displaces the fused metal so that its level is lowered when this body is raised.

I prefer using a U-shaped casting reservoir arranged to rotate about a vertical axis beside the crucible. However, that portion of the reservoir which is connected with the pressure gas conduit can also extend into the crucible, the cross section of which in this case is preferably oval. Under certain conditions, this arrangement is preferred with consideration of the possibility of maintaining the fused metal at high temperature in the crucible.

Preferably the capacity of the casting reservoir is such that one charge contains a quantity of metal which suffices for several casting operations.

In the drawings affixed to this specification and forming part thereof three machines embodying my invention are illustrated diagrammatically by way of example.

In the drawings—

Fig. 1 is a longitudinal section,

Fig. 1^a is a detail view, partly in section, and

Fig. 2 a plan view of the first form, the section in Fig. 1 being taken on the line I—I in Fig. 2.

Figs. 3 and 4 are an elevation and a plan view, respectively, both partly in section, of the second modification,

Figs. 5 and 6 being detail views illustrating parts of this machine, and

Fig. 7 is an elevation,

Fig. 8 is another elevation partly in section, taken from a different angle,

Fig. 9 a plan view partly broken away, and

Fig. 10 an elevation of the crucible during the casting operation of a machine of the third kind.

In all figures *a* is the crucible, *b* the substantially U-shaped casting reservoir. A conduit *z* adapted to supply air or gas under pressure is connected with the longer shank

of the reservoir, while a nozzle *c* is secured in the shorter shank.

Referring now to Figs. 1 and 2, the nozzle *c* extends vertically upwards and the crucible *a* has a lateral extension *d* provided with an opening *f* forming a seat for a ball-shaped valve *h*. The end of the extension is curved at *g* to conform to the curvature of the nozzle *c*. The ball-shaped valve *h* which 10 may be of any suitable material is forced on its seat *f* by the pressure of the fused metal and closes the tap hole.

The casting reservoir *b* is arranged for rotation through an angle of 180° about a 15 vertical axis, the rotation being limited in both its end positions by lateral checks *i* and *k* as shown in Fig. 2. Rotation is imparted to the reservoir *b* by means of a rack *n* which can be displaced in the machine 20 bed by means of a pinion *l* or the like which may be rotated for instance by a hand wheel *m*. The vertical inner face of this rack is further provided with teeth meshing with a 25 pinion *o* which is rotatably carried in the machine bed. The upper face of pinion *o* is formed as one half *p* of a clutch, the corresponding half *q* being secured to the reservoir *b*. The part *p* is held engaged with the part *q* by means of a coil spring *r* 30 whereby reciprocation of rack *n* causes reservoir *b* to rotate from the charging position shown in full lines in Fig. 1 to the casting position shown in dot- and dash-lines, or vice versa.

35 The mould is formed in two parts *s* and *t* which are guided in the machine bed and are adapted to be brought into engagement with one another by suitable means, such as for instance a handle *t'* and a system of 40 links and levers. When the mould is closed, its charging hole *u* is in line with the nozzle *c* of the casting reservoir when this latter is in the casting position.

45 After a molding operation of the machine, the mold *s*, *t* is open, as shown in Fig. 1, and the casting reservoir is in the position shown in dot and dash lines. The rack *n* is also in the position shown in dot and dash lines.

50 By moving the rack *n* in the direction of the arrow *V* in Fig. 1 through the medium of hand wheel *m* and pinion *l* the casting reservoir *b* is rotated 180° in the direction of the arrow *W* in Fig. 2 into the position shown in full lines in Fig. 1, in which it 55 engages the check *k*. The short shank of the casting reservoir is now in the position shown in Fig. 1a in which its nozzle *c* faces the curved face *g* formed in the extension *d*. 60 If the rack *n* is moved farther in the direction of the arrow *V*, the reservoir *b* cannot rotate farther in the direction of the arrow *W*, as the reservoir is arrested by the check *k*. In consequence thereof, the clutch *p*, *q* 65 is disengaged, the pinion *o* which is integral

with the part *p* being lowered against the action of the spring *r*. At the same time a cam face 8 at the end of the reservoir *b* is engaged by a cam face 7 formed on the rack *n* so that the casting reservoir *b* is 70 raised from the position shown in Fig. 1a into the position in full lines shown in Fig. 1. The nozzle *c* of the reservoir *b* enters the recess *g* and at the same time forces the ball *h* away from its seat *f* so that fused 75 metal can flow from the crucible *a* into the casting reservoir through grooves *c'* formed in the nozzle *c* as shown in Fig. 6. When the casting reservoir has been charged, the hand wheel *m* is turned in opposite direction 80 displacing rack *n* counter to the direction of the arrow *V*, that is, to the right. In consequence thereof the casting reservoir *b* is released by the wedge 7 and allowed to return to the position shown in Fig. 1a, 85 clutch *p*, *q* being closed. At the same time the tap hole *f* of the crucible *a* is closed by the ball-shaped valve *h* under the pressure of the fused metal. As the rack *n* moves further to the right, the casting reservoir *b* 90 reaches the position shown in Fig. 1 in dot- and dash-lines where the cam face 8 of reservoir *b* is supported by a cam face 9 formed on the machine bed. The mould *s*, *t* is now 95 closed by the handle *t'* and compressed air or the like introduced into the reservoir through pipe *z*, forcing the metal from the reservoir into the mould *s*, *t*. When after 100 making one or several castings the metal in the reservoir *b* has become exhausted, the reservoir is returned to the charging position. Means may be provided for heating the casting reservoir *b*. Hand wheel *m* can be replaced by a member which is operated automatically from the mould *s*, *t*. 105

In the type of machine illustrated in Figs. 3 to 5 the crucible *a* is provided with a lateral extension 10 in which is formed a tap hole which may extend horizontally or substantially horizontally and may be closed by a ball-shaped valve 12. The nozzle end 110 13 of the casting reservoir is bent horizontally and the outer face of nozzle *c* is curved concentrically with the axis of rotation of the reservoir *b*, as shown in Fig. 4. The extension 10 is formed with a correspondingly curved recess 15. The casting reservoir *b* is operated by means of a rack 16 through the medium of a pinion 17 and a clutch 18, 19 when the rack is moved. The rack 16 is connected with one half 20 of the mould which can be moved toward the other half 22 by a system of links and levers 21. 115

When the machine is started, the casting reservoir is in the position shown in dot- and dash-lines in Fig. 4 and the ball-shaped valve 12 is forced down on its seat. Ribs 23 are provided for guiding the ball-shaped valve 12 so that it is seated properly 120 as shown in Fig. 5. The mould 20, 22 which 125

is open at this time is now closed by moving the part 20 in contact with the part 22 by means of the links and levers 21 in the direction of the arrow 24 in Fig. 3. The 5 rack 16 is moved with the part 20 in the direction of the arrow 24, causing the casting reservoir *b* to rotate in the direction of the arrow 25 in Fig. 4 so that it assumes the position shown in full lines in Figs. 3 10 and 4. When the casting reservoir is in this end or charging position, the nozzle *c* lifts the ball-shaped valve 12 from its seat 11 and the liquid metal flows into the casting reservoir *b*. If the rack is further moved 15 after the casting reservoir has reached its end position, the clutch 18, 19 is automatically disengaged so that the rack can continue its movement to close the mould without influencing the casting reservoir *b*.

20 In the machine illustrated by way of example a rod 26 is connected with the part 20 of the mould on which is formed a cam face 27 which in the charging position of the casting reservoir shown in Fig. 4 causes 25 a tight engagement of the nozzle *c* and the recess 15. In the charging position of the casting reservoir the metal from the crucible *a* flows into the casting reservoir through the small passages *c'* in the nozzle *c*. When 30 the casting reservoir has been charged, the closed mould 20, 22 is moved toward the casting reservoir in the direction of the arrow 30 by suitable means, not shown. The rack 16 moves also in the direction of 35 the arrow and returns the casting reservoir into the dot- and dash-line position in Fig. 4, while at the same time the ball-shaped valve 12 closes the tap hole 11 of the crucible *a*. The casting position of the reservoir 40 is determined by a check 28 in the machine bed. When the casting reservoir *b* engages the check 28, the opening of its nozzle *c* exactly faces the charging opening 29 of the mould 20, 22. By further displacing the 45 mould, it is pressed against the nozzle *c* of the casting reservoir and casting can be effected by introducing gas or air under pressure into the casting reservoir through pipe *z*. The part 22 of the mould is then 50 withdrawn, the casting is ejected and the machine is ready for the next operation.

55 In the machine illustrated in Figs. 7 to 10, the nozzle *c* is secured in a horizontally extending portion of the casting reservoir. The face *c'* of the nozzle *c* is curved in all horizontal planes about the axis of rotation *b'* of the casting reservoir *b*, while the vertical sections of the surface *c'* are curved concentrically to a horizontal axis *c''* of the 60 nozzle, as shown in Fig. 8.

The crucible *a* is provided with a lateral tap hole 11, the outer face 11' of which is curved in accordance with the face *c'* of the nozzle *c*. The casting reservoir *b* is moved 65 from the casting position shown in Fig. 9

in dot- and dash-lines into the charging position shown in full lines in Figs. 7, 8, and 9 by means of a rack 16, a pinion 17 and a clutch 18, 19 as described. The rack 16 is moved by a system of links and levers 21 70 which may also be utilized for closing the mould as described with reference to Figs. 3 to 6.

The crucible *a* is provided with two lugs supporting trunnions 32 about which it can 75 be tilted. The tilting axis of the crucible *a* coincides with the axis *c''* in Fig. 8. At a point of the crucible opposite the trunnions 32 the crucible is suspended on a cable 33, to the other end of which is secured a balance weight which tends to hold the crucible with the fused metal in horizontal or substantially horizontal position during the charging of the casting reservoir *b*. A partition 35 is arranged in the crucible as 80 shown in Figs. 8, 9, and 10, which protects the discharge opening from scum or the like.

This machine operates as follows:—

During charging the casting reservoir is 90 in the position shown in full lines in Figs. 7, 8 and 9, while the crucible *a* is in the horizontal or substantially horizontal position shown in Fig. 8. Liquid metal flows into the casting reservoir *b* from the crucible 95 through the tap hole 11 which in this position of the crucible is slightly below the level of the metal. When the casting reservoir *b* has been charged, the crucible *a* is turned on its trunnions 32 into the position 100 shown in Fig. 10 so that the level of the metal falls below the tap hole 11. The casting reservoir can now be rotated about its axis *b'* into the casting position shown in dot- and dash-lines in Fig. 9, whereupon 105 compressed air is admitted through pipe *z* and casting is performed after the mould has been moved toward the casting reservoir, as described.

When the charge in the casting reservoir 110 has become exhausted after casting one or several pieces it is returned to the charging position by displacing the rack 16 so that the nozzle engages the seat 11' of the crucible which is in the position shown in Fig. 10. Thereupon the crucible *a* is tilted upwards into its horizontal or substantially horizontal position shown in Fig. 8 causing 115 the level of the fused metal to rise beyond the tap hole 11, and the casting reservoir 120 is recharged.

As the faces *c'* and 11' are concentric to the axis *c''* and the crucible is tilted about this axis, the crucible and the casting reservoir are tightly connected notwithstanding 125 their relative rotation.

The balance weight 34 maintains the level of the fused metal in about the position shown in Fig. 8, even if less metal is in the crucible than shown in Fig. 8. In this case 130

the balance weight 34 slightly raises the crucible on the side opposite the tap hole so that the fused metal rises again to the level shown in Fig. 8.

6 I wish it to be understood that I do not desire to be limited to the exact details of construction shown and described, for obvious modifications will occur to a person skilled in the art.

10 I claim:

1. A casting machine comprising a mold, a crucible for fused metal having an outlet port, a casting reservoir arranged exteriorly of the crucible and movable relatively thereto and into register with said port to receive metal from below the surface of the metal in the crucible, said reservoir being also movable into contact with the mold, and means for acting on said reservoir with compressed gas to discharge the metal from the reservoir into the mold.

2. A casting machine comprising a mold, a crucible for fused metal having an outlet port, a casting reservoir arranged exteriorly of the crucible and provided with a nozzle, said reservoir being movable relatively to the crucible for bringing the nozzle into register with said port, to permit the reservoir to receive metal from below the surface of the metal in the crucible, said reservoir being also movable into engagement with the mold for discharging its metal into the mold, and means for acting on said reservoir for compressed gas to discharge the metal therefrom.

3. A casting machine as claimed in claim 1 including mechanism for alternately connecting said reservoir with said crucible and said mold.

40 4. A casting machine as claimed in claim 1 in which the crucible is stationary and the casting reservoir is oscillatable.

45 5. A casting machine as claimed in claim 1 including mechanism for oscillating the reservoir to bring the same alternately into engagement with the crucible and mold.

6. Casting machine comprising a machine bed, a mould, a casting reservoir adapted to be rotated about a vertical axis and to be displaced in parallel to said axis, a crucible means for supplying gas under pressure to said reservoir, a rack arranged to rotate and to displace said casting reservoir, cam faces formed on said casting reservoir, said rack and said machine bed and adapted to cooperate with each other and mechanism for displacing said rack.

60 7. Casting machine comprising a machine bed, a mould, a casting reservoir adapted to be rotated about a vertical axis and to be displaced in parallel to said axis, a crucible, means for supplying gas under pressure to said reservoir, a rack arranged to rotate and to displace said casting reservoir, resilient power transmitting mechanism interposed

between said rack and said reservoir, cam faces formed on said casting reservoir, said rack, and said machine bed, and adapted to cooperate with each other and mechanism for displacing said rack.

8. Casting machine comprising a mould, a crucible and a casting reservoir adapted to be rotated about a vertical axis and to be displaced in parallel to said axis, so as to alternately engage with said mould and said crucible, a rack adapted to rotate and to displace said casting reservoir, resilient power transmitting mechanism interposed between said rack and said reservoir, mechanism for automatically releasing said power transmitting mechanism after the said reservoir has completed its stroke, mechanism for displacing said rack and means for introducing into said reservoir gas under pressure.

9. A casting machine comprising a mold, a crucible spaced from the mold and having an outlet port, mechanism for opening and closing said mould, a movable casting reservoir arranged exteriorly of the crucible and having a nozzle adapted to register with the outlet port to receive metal from below the surface of the metal in the crucible, said reservoir being adapted to be connected with the mold, and means for introducing into said reservoir a gas under pressure for discharging the metal from the reservoir into the mold.

10. Casting machine comprising a mould, a stationary crucible, a tap valve in said crucible, a movable casting reservoir, means for introducing into said reservoir a gas under pressure and mechanism for alternately connecting said reservoir with said metal supply and said mould, mechanism for alternately connecting said casting reservoir with said mould and said crucible and a nozzle on said reservoir capable of opening said valve.

11. A casting machine as claimed in claim 1 in which the reservoir is movable about a substantially vertical axis and includes a substantially U-shaped member.

12. A casting machine comprising a mold formed of relatively movable sections, mechanism for moving one of said sections for opening and closing the mold, a crucible having an outlet port, a casting reservoir arranged exteriorly of the crucible and having a nozzle adapted to be brought into register with said port for receiving metal from below the surface of the metal in said crucible, means for introducing gas under pressure into said reservoir, and mechanism for opening and closing said mold and for displacing said mold, said mechanism being adapted to connect said reservoir with said crucible when said mold is closed and to connect said reservoir with said mold when said mold is displaced.

13. Casting machine comprising a mould, a stationary crucible with a lateral tap hole, a casting reservoir adapted to be rotated, means for supplying gas under pressure to said casting reservoir, a horizontal bend formed at one end of said reservoir, a nozzle in said bend, a seat formed in said tap hole and adapted to be engaged by said nozzle, the faces of said nozzle and seat being curved about the axis of rotation of said reservoir, and mechanism for alternately connecting said reservoir with said mould and said crucible.
14. Casting machine comprising a mould, a stationary crucible with a tap hole, a valve adapted to close said tap hole, a casting reservoir, a nozzle on said reservoir capable of opening said valve, means for supplying gas under pressure to said casting reservoir, mechanism for rotating and displacing said casting reservoir and means for alternately connecting it with said mould and said crucible, said displacing mechanism being adapted to raise said reservoir to a position in which said nozzle engages said tap hole.
15. A casting machine comprising a machine bed, a mold, a crucible with an outlet port, a casting reservoir adapted to be rotated about a vertical axis and arranged exteriorly of the crucible, said reservoir having a nozzle adapted to register with said port and to receive metal from below the surface of the metal in said crucible, said reservoir being also engageable with said mold, means for supplying gas under pressure to said reservoir for discharging the metal from the reservoir into said mold, a rack arranged to oscillate said reservoir, cam faces formed on said reservoir and crucible and adapted to cooperate with each other, and mechanism for displacing said rack, said cam faces being adapted to guide the nozzle end of the reservoir into engagement with the crucible.
16. Casting machine comprising a mould, a crucible for fused metal, a movable casting reservoir, means for introducing into said reservoir a gas under pressure, mechanism for alternately connecting said reservoir with said crucible and said mould and a nozzle on said reservoir comprising a central passage and a by-pass.
17. A casting machine comprising a mold having an inlet, a crucible to contain fused metal and provided with an outlet port, an oscillatable casting reservoir having a nozzle adapted to register with said outlet port to receive metal from below the surface of the metal in the crucible, said nozzle being adapted to engage the inlet of the mold for discharging the metal into the mold, means for introducing gas under pressure into the reservoir for discharging the metal from the reservoir, and means for oscillating said reservoir.
18. A casting machine as claimed in claim 17 in which said outlet port is normally closed by a valve.

In testimony whereof I affix my signature.

ALBERT KAUFMANN.
